(57) **CLAIM**

The ornamental design for bench for modular seating furniture, as shown and described.

DESCRIPTION

FIG. 1 is a front perspective view of a first embodiment showing the claimed design;

FIG. 2 is a front view thereof, wherein the rear view is identical to this front view;

FIG. 3 is a right side view thereof; wherein the left side view is identical to this right side view;

FIG. 4 is a top view thereof;

FIG. 5 is a front perspective view of a second embodiment showing the claimed design;

FIG. 6 is a front view thereof, wherein the rear view is identical to this front view;

FIG. 7 is a right side view thereof, wherein the left side view is identical to this right side view;

FIG. 8 is a top view thereof;

FIG. 9 is a front perspective view of a third embodiment showing the claimed design;

FIG. 10 is a front view thereof, wherein the rear view is identical to this front view;

FIG. 11 is a right side view thereof, wherein the left side view is identical to this right side view;

FIG. 12 is a top view thereof;

FIG. 13 is a front perspective view of a fourth embodiment showing the claimed design;

FIG. 14 is a front view thereof; wherein the rear view is identical to this front view;

FIG. 15 is a right side view thereof, wherein the left side view is identical to this right side view; and,

FIG. 16 is a top view thereof.

The dashed broken lines shown on the upper portions of the article, along the edges of the ends of the article, and through the middle section of the article, are included for the purpose of illustrating stitching forming part of the claimed design.

(Continued)

The stippled broken lines shown on the base portions of the article are portions of the article forming no part of the claimed design.

1 Claim, 14 Drawing Sheets
